Fig. 7.

The diagram shows a cross-section of a double-walled structure, possibly a tire. It consists of an outer layer 14 and an inner layer 13. Between these layers are several internal components: a top layer 16, a middle layer 12, and two bottom layers 10. The top layer 16 is positioned above the middle layer 12, and the two bottom layers 10 are positioned below the middle layer 12. The diagram illustrates the layered construction and the relationship between the different components.

UNITED STATES PATENT OFFICE.

GEORGE W. LAWSON, OF NEW YORK, N. Y.

MARINE PROPELLER.

Application filed October 7, 1920. Serial No. 415,317.

To all whom it may concern:

Be it known that I, GEORGE W. LAWSON, a citizen of the United States, and a resident of the city of New York, borough of the Bronx, county of Bronx and State of New York, have invented a new and Improved Marine Propeller, of which the following is a full, clear, and exact description.

This invention relates to propellers and 10 more particularly to an improvement in the construction of marine screw propellers.

The invention contemplates and aims for one of its principal objects to provide a construction which will increase the power 15 of any propeller of a given size with a minimum expenditure of energy, and to this end, one of the main features resides in forming the blades with a working face of substantially the same width throughout, from the 20 free end of each blade to the base, and in which the base at its juncture with the hub, is of a greater pitch relative to the remainder of the blade.

A further object in view is to construct a 25 propeller in which the leading edge of the blade extends in advance of the forward end of the hub to obtain an initial purchase or grip on the water forward of the hub to avoid suction.

30 A still further object of the invention is to provide a screw propeller having novel features of construction which materially add to the efficiency of the same, without materially increasing the cost of production.

35 With the above mentioned and other objects in view, some of which will more clearly appear hereafter, reference is made to the following specification, the appended claim and the accompanying drawings forming a part of this application, in which;

Figure 1 is a front elevation of a propeller constructed in accordance with the 45 invention.

Figure 2 is a side view thereof.

Figure 3 is a cross sectional view through one of the blades taken approximately on the line 3—3 of Figure 1.

Figure 4 is a similar view on the line 4—4 50 of Figure 1.

Figure 5 is a similar view on the line 5—5 55 of Figure 1.

Figure 6 is a similar view on the line 6—6 60 of Figure 1.

Figure 7 is a similar view on the line 7—7 65 of Figure 1.

Referring to the drawings by characters of reference, 10 designates the hub of the propeller and 11 the blades extending radially therefrom. The blades are of identical formation and therefore a description of one will suffice to explain the features of construction of all of the same. Each blade is provided with a substantially flat working 70 face 12 having the desired pitch or angular relation to the axis of the hub. The rear face is properly curved as at 13 to produce a stream line effect. The working face of the blade is of substantially the same width throughout the length of the blade from its outer free end to its base. The forward or leading edge 14 of the blade is in advance of the forward end of the hub whereby the blade will obtain an initial purchase or grip 75 on the water forward on the hub to minimize suction at this point. Immediately adjacent the juncture of the blade with the hub, the pitch of the same is increased as illustrated at 15. This increased pitch curves at 80 a point where the proportionate distance traveled is less than the distance traveled by the remainder of the blade, whereby no substantial increase in resistance is offered at this point. The various cross sections 85 taken through the blade shown in the several views of the drawing, illustrate the variations in the working surfaces of the blade to show the gradual increase of the pitch from the outer free end of the blade 90 to the base at the point of its juncture with the hub. The rear or following edge 16 of the blade is in advance of the rear end of the hub in order to reduce to a minimum suction at this point caused by the action of 95 the water leaving the following edge 16.

From the foregoing it is to be understood that the right is reserved to embodiments

other than those actually illustrated herein, to the full extent indicated by the general meaning of the terms in which the claim is expressed and by variations in the phraseology of the same.

Having thus described my invention, I claim as new and desire to secure by Letters Patent:—

A propeller comprising a hub, and a series of radial blades helically arranged thereto, each of said blades having a compound

pitch, the leading edge of each of said blades being convex and extending in advance of the forward end of the hub and the tip of the blade, each of said blades being so formed that the greatest convexity of the entering edge is located approximately at the greatest width of the blade, and the greatest pitch of the blade initiates at the greatest width of the blade and increases therefrom to the following edge thereof.

GEORGE W. LAWSON.
